UNITED STATES PATENT OFFICE

2,510,949

PIPE JOINT

Lawrence J. Bergsten, Minneapolis, Minn.

Application December 1, 1945, Serial No. 632,220

2 Claims. (Cl. 285—35)

1

This invention relates to suction cleaners of the type generally used for general household cleaning and for similar purposes.

My invention is particularly adapted for use in connection with that type of suction cleaner which includes a horizontally disposed substantially cylindrical casing within which is mounted a fan and a dust collecting bag. One end of the casing is provided with an air inlet to which a hose may be attached and the other end of the casing is provided with an air outlet. This type of suction cleaner is customarily provided with sets of runner elements which support the casing and permit it to be drawn across the floor.

One of the objects of my invention is to provide a suction cleaner construction having a substantially horizontally disposed body with improved means for facilitating movement of the cleaner across the floor without damage to rugs or polished floor surfaces.

Another object of the invention is the provision of an improved mounting for the elements supporting the cleaner.

Another object of the invention is to provide an improved simplified air inlet head and ball joint support for the inlet hose.

A further object of the invention is to provide an improved fumigating attachment for suction cleaners and an improved mounting therefor.

These and other objects and advantages of the invention will more fully appear from the following description made in connection with the accompanying drawings, wherein like reference characters refer to the same or similar parts throughout the views, and in which:

Fig. 1 is a plan view of a cleaner embodying my invention;

Fig. 2 is a side elevation thereof with portions of the casing and inner mountings broken away with the fumigating attachment shown in dotted lines;

Fig. 3 is an enlarged, vertical section taken longitudinally through the forward or air inlet portion of the apparatus; and

Fig. 4 is a longitudinal vertical section through the fumigating attachment.

Referring more particularly to Figs. 1 and 2, the apparatus includes an outer casing 5 of generally cylindrical shape with an air inlet element 6 and an air outlet generally indicated at 7. Within the casing 5 is a motor 8 supported by rubber mountings 9 and said motor has a fan unit driven thereby. The fan is of conventional structure and is not shown. The forward end of the casing carries a fabric bag 11 which is

adapted to receive air drawn in through the intake 6 and to filter dust from said air, the cleaned or filtered air being drawn rearwardly through the bag and out of the outlet 7. The motor is controlled by switch element 12 which is connected by a relatively long pair of wires 13 to a conveniently located electrical outlet attachment. A flexible hose 14 is detachably connected to the air inlet element 6 in a manner to be described below. A suitable handle 15 is mounted on the upper side of the casing 5.

When apparatus of this type is used the cleaner mechanism supported by and within the casing 5 rests upon the floor and as the operator moves to different parts of the room where rugs or finishings are being cleaned, the casing 5 is moved by pulling upon the flexible hose 14. Heretofore, apparatus of this type has been supported by a plurality of runners which are adapted to slide over the rug or bare floor surface, or the casing has been supported entirely by rollers. Naturally, a sliding element products considerable friction and undue wear and other damage to rugs and polished floor surfaces. Where the casing is supported completely by rollers, its movement is too free and cannot be easily controlled. Frequently when this type of cleaner is pulled across the floor, it bumps into furniture and scratches it or otherwise injures the finish. In this construction shown, in the drawings, I provide a pair of rear wheels 16 which are mounted upon axles 17, each of said wheels having an individual axle mounted between the lower rear side walls of the casing 5 and webs 18 which are preferably cast integrally with the rear end of the casing 12. The webs 18 in combination with cooperating webs 19 form wells for the rear wheels 16 and separate the wheel mountings from the interior of the casing. The forward end of the casing is supported by a pair of metal strips 20 which, as best shown in Fig. 2, extend downwardly from the casing and have flat floor engaging portions 20a. The strips 20 extend through the bottom of the casing and as shown in Figs. 2 and 3, are cushioned in blocks of rubber 21. Plates 22 on the upper sides of the rubber blocks 21 are connected to the bottom of the casing by means of rivets 23. It will be noted that the supporting strips 20 are positioned adjacent the forward end of the casing 5 a considerable distance from the rear wheels 16 so that when the operator of the apparatus wishes to move the same by pulling on the flexible hose 14 the forward end of the casing will be elevated to some extent due to the pull on the hose 14 and

the height of the operator above the casing, and the apparatus will move across the floor supported by the hose and by the rear wheels 16. In addition the motor and suction fan are located adjacent the rear end of the casing and the wheels 16, these two elements constituting the heavier parts of the apparatus and concentrating the weight in the rear thereof. This concentration of weight also assists in elevating the front end of the casing when it is being moved. Thus, the considerable wear incident to sliding of the cleaner across the floor surface is eliminated and rugs and floor finishes are in no way injured. It will be seen that I have combined the advantages of the roller support with those of a slide element so that the device can be easily moved, but at the same time, it is quickly brought to rest when the user ceases to pull on the hose, and there is absolutely no danger of the machine drifting across the floor and into furniture and other articles. In addition, the combination of the roller and slide is of considerable advantage when the device is placed on surfaces which are not necessarily level such as on the running board of a motor vehicle when cleaning the upholstery and other interior parts of the vehicle. Furthermore, the rubber mounting of the metal strips 20 naturally reduces any vibration which might otherwise be transmitted from the apparatus to a highly polished floor.

In Fig. 3, there is shown the details of the forward removable head of the casing and the connection between the casing and the flexible hose 14. The casing head 24 is provided with a central aperture 25 and, as is illustrated said aperture is provided with a forwardly and upwardly extending lip portion 26. The material in the head 24 which defines the opening 25 is rounded as shown, to provide a portion of a rounded socket. The other portion of said socket is provided by a more or less disc-like element or plate 27 which has a central opening defined by a flange 28 having a turned edge 28a. A gasket 28b is retained by the flange 28 and provides a portion of the socket for the ball 45. This gasket serves effectively to prevent air leaks past the ball element and also acts to clean the ball when the joint is moved. A plurality of short bolts 29 extend through the disc-like element 27 and into bosses 30 on the inner side of said head. The lower portion of the head 24 is provided with a hook 31 which is adapted to fit into an eye portion 32 on a metal ring 33 which is secured to the main casing. The ring may be secured to the main casing by bolts 34 which extend through the brackets 35, the latter being connected to the casing. The bolts are threaded into the ring 33. The upper portion of the head 34 is provided with a notch 36 to receive the hooked end 37 of a fastening element which includes a forward portion 38 pivotally secured at 39 to an operating lever 40. The lever 40 is pivotally mounted at 41 to lugs 42 on the main casing. When the head 24 and its cooperating disc-like element 27 are clamped into place, a flange 43 on said disc-like element clamps a ring 44 between it and the ring 33 which is secured to the casing. The ring 44 is secured to and holds in position the dust collecting bag 11.

The socket formed by the central openings in the head 24 and the disc-like element 27 is adapted to movably receive the more or less ball-shaped element 45. The latter has a central opening 46 therethrough and the outer end of said opening is defined by a lip upon which is

secured a collar 48. The flexible hose 14 has a tubular metal element 49 extending from its end, said element being insertable in the opening 46 through the ball 45 and a corrugation 50 limits the inward movement of the sleeve 49 with respect to the apertured ball 45. A second sleeve 51 is secured outside of the end of the flexible hose 14 and extends inwardly therefrom in spaced relation to the inner sleeve 49. A spring tongue 52 which is operable by a button 53 is provided with a hooked end 54 which is adapted to slip into an opening 55 in the flanged outer edge of the collar 48 and behind a portion of said flanged end to detachably secure the hose to the air inlet provided by the ball 45. It will be noted that the forwardly and upwardly extending lip on the head 24 limits downward movement of the ball 45 and the end of the hose 14. However, considerable upward angular movement of the end of the hose is permitted due to the shape of the head defining the opening 25 in said head. The ball is made of insulating material such as "Bakelite" for the reason that sometimes short circuits develop in the apparatus, and usually the hose 14 is reinforced by a helical wire, and in some machines of this type it is relatively easy to get a shock if the user is holding the hose and at the same time, touches an electrical outlet switch. It will be noted that in any position to which the ball and hose end may be turned, the ball of insulating material still cuts off any electrical communication between the machine itself and the hose.

In Fig. 4 there is shown a fumigating attachment which comprises cooperating shell portions 56 and 57. These may be separably connected by means of a bayonet joint, threads or any other suitable connection. The shell 57 is provided with an annular inner groove 58 which receives a spring ring 59, the latter holding the arms 61 of an air deflector 66. The tubular mouth 61 of the shell 57 is provided with an inner groove 62 within which a filter element 63 is secured and the opposite end of the attachment is provided with a mouth 64 and a filter element 65. Within the shell 57 between the filters 63 and 65 a fumigating material such as paradichlorbenzine crystals may be placed. The fumigating attachment is indicated in dotted lines in Fig. 2 with one of its mouth portions or open ends inserted in the air outlet 7 at the left-hand end of the cleaner casing. The air outlet includes a sleeve previously indicated by the numeral 7, said sleeve having an inwardly turned flange 7a below which is positioned a ring 7b. The collar 7 and ring 7b are supported in the rear portion of the main casing of the machine as is clearly shown.

The substantially vertical positioning of the fumigating attachment in the vertically disposed outlet opening of the cleaner has important advantages. The attachment when in use for fumigating a room will direct air upwardly and materially assist in defusing fumigated air throughout the room, particularly since the apparatus is resting upon the floor. Another advantage of the vertical disposition of the fumigating attachment is that when fumigating material in lump or granulated form is placed in the fumigator, the material will be evenly distributed across the flow of air, and said air will be more thoroughly mixed with gases from the fumigant. With the fumigating attachment shown in the substantially vertical position in Fig. 2, it will be seen that the crystals of fumigant will slide

to the bottom of the device and rest upon the screen 65 relatively close to the motor 8. There is considerable heat generated by the motor and the warmth of the air flowing through the outlet and through the fumigator causes more rapid vaporization of the fumigant and the results are naturally more effective. When the fumigating attachment is secured to the end of the hose 14 for treating furniture cushions and other articles which are inconvenient to fumigate with the attachment on the machine itself the end 61 is secured to the hose. This is done so that the deflector 66 will direct air radially against the crystals which might be lying in the lower intermediate part of the casing. The deflector is not important when the device is used in the position illustrated in Fig. 2 but does have an important function when the fumigating attachment is held in a horizontal position.

When the fumigator is used for moth-proofing furniture, pianos and for similar purposes, it may be of advantage to utilize the flexible hose 14 to confine the flow of fumigant-bearing air. The hose may be connected on the outlet end of the fumigator or it may be directly connected to the air outlet of the cleaner and the fumigating attachment secured to the opposite end of the hose. If the hose is connected to the cleaner at the air outlet the spring element 52 with its hook end 54 on the end of the hose may be connected beneath the flange 7a on the collar 7. This would prevent accidental displacement of the hose as it is being moved to different positions.

From the foregoing description it will be seen that I have provided a suction cleaner construction which is not only easy to manipulate and move around a room, but which is so supported on the floor that it can be moved without damaging rug texture or floor finishes. It does not move so freely as to run wild and damage itself or articles of furniture, however. As above described, when the cleaner is moved the metal strips 20 are raised out of contact with the floor and the cleaner is moved on the rollers 16 while the hose 14 is supported and drawn by the operator. The concentration of weight toward the rear of the cleaning apparatus also assists in this movement on the rollers with the strips 20 off of the floor. The front end construction with its improved ball and socket arrangement is one which is simple to assemble and extremely efficient in use. In addition the cleaner can be used as a combination cleaner and fumigator or as a fumigator alone, and the fumigating attachment can be quickly applied without resorting to the use of tools or the manipulation of thumb screws or bolts.

It will, of course, be understood that various changes may be made in the form, details arrangement and proportions of the various parts without departing from the scope of my invention.

What I claim is:

1. Mechanism for flexibly connecting the fluid inlet of a machine such as a suction cleaner with a flexible hose to provide both communication and draft means for said machine, having in combination an annular ball-receiving socket disposed generally horizontally and comprising gen-

erally, an internal zone of a hollow sphere, a ball-like swivel element complementarily shaped to said socket and retained therein with freedom for universal swivel adjustment relatively to said socket, a compressible liner gasket interposed between said socket and swivel member for air sealing the relationship between socket and swivel element, said socket having an outwardly protruding lip in the lower portion thereof conforming to the general internal hollow sphere zone shape of the socket for engaging said swivel member to limit the downward movement thereof, to substantially horizontal position, a rigid tubular element inserted at one end in a flexible hose and projecting beyond said end, said ball-like swivel member having an enlarged axial and cylindrical passage therethrough, said tubular element being detachably inserted in sealed relation within said passage and a connector between the outer end of said swivel element and said hose for detachably retaining said hose in connected relation with said swivel element.

2. Mechanism for flexibly connecting the fluid inlet of a machine such as a suction cleaner with a flexible hose to provide both communication and draft means for said machine, having in combination, a plate forming at least a portion of one of the walls of said machine at one end thereof, said plate having a medially disposed circular aperture defined by an inturned annular flange shaped generally in accordance with an internal zone of a hollow sphere taken in an area disposed at one side of the equator of said sphere, a ball-swivel element constructed of somewhat compressible material and complementarily shaped to said flange and seated therein, a removable annular member secured to said plate and having an inner peripheral portion of complementary shape to said ball and surrounding the same in a zone engaging a portion of said ball member at the opposite side of the equator thereof, said peripheral portion with said flange forming a retaining socket for said ball, said removable annular member having a widened lip portion in its periphery adjacent the lower part thereof for underlying said ball to limit downward swinging movement thereof, said ball member having a relatively large cylindrical aperture extending therethrough, a rigid tubular element inserted and fixed at one end in an end of a flexible hose and projecting beyond said end, said projecting portion being detachably inserted in sealed relation within the apertured portion of said ball and a draft connector between the outer end of said ball member and said hose for detachably retaining said hose in connected relation with said ball member.
